UNITED STATES PATENT OFFICE.

RICHARD W. HICKS, OF AKRON, OHIO.

ATTACHMENT FOR FRUIT CRATES.

Application filed March 11, 1922. Serial No. 542,824.

To all whom it may concern:

Be it known that I, RICHARD W. HICKS, a citizen of the United States, residing at Akron, in the county of Summit, State of Ohio, have invented certain new and useful Improvements in Attachments for Fruit Crates, of which the following is a specification.

My invention relates to improvements in 10 attachments for crates, of the specific type commonly used for shipping and storing perishable goods, such as oranges or similar fruits.

In dealing in commodities of the above 15 designated character, a practical method of displaying the goods, in bulk, is of recognized advantage, particularly when it enables the dealer to show that the lower layers of such goods have not deteriorated 20 through packing and shipping. An attractive arrangement of the goods is also highly desirable, but is difficult to attain, in displaying such goods as oranges, lemons, or the like, because of their circular character.

25 With the foregoing in mind, the present invention is directed toward providing a practical attachment for crates, such as are used, for instance in packing oranges, whereby the crates may be stacked in tiers, and the 30 fruit therein exposed to view in an attractive manner, the bulk of the fruit being displayed without necessitating removing any of it from the crate.

Another object of the invention is to provide 35 such an attachment that is capable of being collapsed or folded and hence stored in a relatively small space when not in use.

Other objects, and advantages, such as 40 simplicity of construction, and relatively low cost of manufacture are also comprehended by my invention, as will appear when the nature of the invention is more fully understood, the following description, and the accompanying drawing constituting 45 a complete disclosure of certain preferred embodiments thereof.

In the drawings:

Fig. 1 is a perspective view illustrating 50 the application of my invention,

Fig. 2 is a perspective view, of the attachment, with portions broken away,

Fig. 3 is a rear elevational view of a modified form of the invention,

Fig. 4, is a sectional view on an enlarged 55 scale of a portion of Fig. 3, and

Fig. 5 is a fragmentary, rear elevational view illustrating another modification of the invention.

As best shown in Fig. 1 of the drawings 60 my attachment is in effect a bracket designated as a whole by the numeral 1. It is designed for application to the lower edge of a fruit crate, such as that shown at 2, after the slats of one side thereof have been removed, 65 and in such position thereon that the crates may be stacked, one upon the other, with their open side to the front, and the fruit therein prevented from rolling out. To this end I provide a guard plate 3, of substantially 70 the same length, in its preferred form, as that of the crate, and I provide hinged end members 4, upon the guard of such form that they may be fastened to the crate and support the guard 3 in an upwardly inclined position relative to the lower edge thereof. 75 In order to provide for sufficient rigidity in the plate 3 and at the same time effect a light construction I preferably form the guard 3 from sheet tin and reinforce it at its upper 80 and end edges by a stiff wire frame 5, best shown in Fig. 2, the edges of the guard being rolled over the frame as therein shown.

I may however elect to utilize an extensible guard in which event a telescopic frame 6 is provided as shown in Fig. 3. In this 85 form of the invention the upper wire 7 of the frame 6 is provided with a bore 8 and a reduced portion 9 adapted to slide therein, forming in effect relatively movable sections. The guard in this instance is also formed of 90 sections which overlap at their contiguous ends and are carried respectively by the sections of the frame 6.

As shown in Fig. 5 such a guard may be 95 formed of wire 11 with a reinforcing frame 12 of the character used in the preferred form of the invention.

The end members 4 in each instance are 100 substantially the same. They are preferably formed of sheet tin and are reinforced at their upper edges as at 6. Each member is formed, preferably, in the shape of a right angled triangle, its arrangement relative to the guard 3 being such that one of its right angled edges 14 is hinged thereto, and its other right angled edge 15 is uppermost 105 when the attachment is applied to the crate. Through this arrangement the ends 4 may be folded against the guard 3, when it is not in use, without their edges projecting 110

beyond the edges of said guard, and they may therefore be stacked in a relatively small space.

At the extreme outer portion of each end member a nail opening 16 is provided through which a nail or screw may be inserted and the end members 4 secured to the ends of the crate. If desired a tab 17 may be attached to the middle portion of the guard, as shown in Figs. 1 and 2, which may be bent back under the crate and nailed thereto to prevent outward bulging at this point from the weight of the fruit.

By reference to Fig. 1, it will be seen that when the crate is opened and turned on one side, the guard 3 of the attachment is positioned with its lower edge resting against the lower edge of the crate, and projects at an angle upwardly and outwardly from said edge. The end members are positioned at right angles to the plate and by virtue of their form, and attachment to the crate, serve to securely hold the guard in the position described. Obviously the fruit of its own weight will gravitate toward the guard and some of those that were at the bottom of the crate will roll to the front, against the guard. Thus it is displayed in the form of a pyramid or bank which shows the fruit throughout the full depth of the crate and in an attractive manner.

Although I have shown and described a preferred form of my invention, together with certain logical modifications thereof, it is to be understood that the present disclosure is illustrative in nature, and is not to be construed as limiting this invention to the precise constructions disclosed, unless such limitations are particularly specified in the claims appended hereto and forming a part of this specification.

Claims:

1. A device adapted to be attached at the open side of a crate comprising, a guard of

substantially the length of the crate, and 45 hinged end members constructed to secure the guard to the crate in an inclined position relative to one edge of the open side thereof with one edge of the guard resting upon said edge of the crate.

2. A device adapted for attachment at the open side of a crate comprising, a guard substantially coextensive with the length of the crate having reinforced edges, and hinged end members constructed to secure 55 the guard to the crate in an inclined position relative to one edge of the open side thereof with one edge of the guard resting upon said edge of the crate.

3. A device adapted for attachment at the open side of a crate comprising, a guard substantially coextensive with the length of the crate, triangular end members hinged to the guard and constructed to secure said guard to the crate in an inclined position 65 relative to one edge of the open side thereof, and a tab for securing the intermediate portion of the guard to the crate.

4. A device adapted for attachment at the open side of a crate comprising, a guard substantially coextensive with the length of the crate having reinforced edges, hinged end members constructed to secure the guard to the crate in an upwardly and outwardly inclined position relative to one edge of the 75 open side thereof, said members also having reinforced edges, and a tab for securing the intermediate portion of the guard to the crate.

5. A device adapted for attachment at the open side of a crate comprising, an extensible guard having reinforced edges, and hinged triangular end members constructed to secure the guard to the crate in a forwardly and upwardly inclined position relative to one edge of the open side thereof.

RICHARD W. HICKS.
